(57) **CLAIM**

The ornamental design for a shopping trolley, as shown and described.

DESCRIPTION

FIG. 1 is a front elevational view of a shopping trolley showing our new design in a folded state.

FIG. 2 is a rear elevational view thereof.

FIG. 3 is a right side elevational view thereof.

FIG. 4 is a left side elevational view thereof.

FIG. 5 is a top elevational view thereof.

FIG. 6 is a bottom elevational view thereof.

FIG. 7 is an isometric view thereof.

FIG. 8 is a front elevational view showing the shopping trolley in a deployed state.

FIG. 9 is a rear elevational view thereof.

FIG. 10 is a right side elevational view thereof.

FIG. 11 is a left side elevational view thereof.

FIG. 12 is a top elevational view thereof.

FIG. 13 is a bottom elevational view thereof; and,

FIG. 14 is an isometric view thereof.

The dotted lines in FIG. 13 are intended to indicate portions of the shopping trolley not forming part of the claimed design.
